UNITED STATES PATENT OFFICE.

ADOLPH PETER GUSTAFSON, OF CHICAGO, ILLINOIS, ASSIGNOR TO M. SCHULZ COMPANY,
OF CHICAGO, ILLINOIS.

TRACKING DEVICE FOR AUTOMATIC MUSICAL INSTRUMENTS.

1,313,226.

Specification of Letters Patent. Patented Aug. 12, 1919.

Application filed November 19, 1915. Serial No. 62,265.

To all whom it may concern:

Be it known that I, ADOLPH P. GUSTAFSON, a citizen of the United States, residing at Chicago, in the county of Cook and State of Illinois, have invented a certain new and useful Improvement in Tracking Devices for Automatic Musical Instruments, of which the following is a full, clear, concise, and exact description, reference being had to the accompanying drawings, forming a part of this specification.

My invention relates to tracking devices for automatic musical instruments, especially to instruments employing a traveling music sheet or web.

The principal object of the invention is to arrange for the simple and effective control of the traveling sheet or web so as to place it in proper tracking position at or before the beginning of the playing of the instrument, and to maintain it in such proper tracking position throughout the playing.

In the accompanying drawings Figure 1 is a front elevation of a part of an automatic musical instrument and a traveling music sheet therein, together with tracking mechanism embodying my present invention;

Fig. 2 is a rear elevation of the upper portion of the mechanism shown in Fig. 1;

Fig. 3 is an end view of the left hand end of the mechanism shown in Fig. 1;

Fig. 4 is a view of the right hand end of the same;

Fig. 5 is a cross section taken on line 5—5 in Fig. 1;

Fig. 6 is an elevation similar to Fig. 1, of a modified form of the invention;

Fig. 7 is a cross section taken on line 7—7 in Fig. 6;

Fig. 8 is a perspective view of a portion of the device shown in Figs. 6 and 7.

In the drawings, and especially in Figs. 1-5, inclusive, I show a music spool 1 carrying a sheet or web 2 and a take-up roll 3, these parts being such as are ordinarily employed in automatic musical instruments commonly known as player pianos.

A tracker 4 is also shown with the music sheet 2 passing over the same. The tracker 4 is supported at its ends by upright or

vertical side members 5 and 6, which latter also support and carry the upper spindles for the roll 1 and the spool 3.

As a desirable arrangement for carrying out my invention I provide a pair of arms 7 and 8 which are mounted upon a rod 9, said arms 7 and 8 being secured to the rod 9 in such position that said arms will fit just inside of the ends or flanges 10—10 at the ends of the spool 1. The rod 9 is mounted for rotation or rocking motion, as for example by mounting its ends in the side members 5 and 6 whereby by rocking said rod 9 the arms 7 and 8 may be thrown downward into position between the flanges 10 of the music roll 1, as shown in full lines in Fig. 5, or may be swung upwardly so as to be out of engagement and free from the spool 1, as shown in dotted lines in Fig. 5. Thus the roll 1 may be set in proper place to cause the proper trackage of the music sheet 2, by swinging the arms 7 and 8 down so as to engage the flanges 10 on the roll 1, as shown in Fig. 1, the arms 7 and 8 being so positioned that when in engagement with the roll 1, as shown, said roll will be so positioned that its music sheet will track properly with the tracker board.

As an arrangement for controlling the arms 7 and 8, preferably automatically, I provide a pneumatic 12 on the back of the music spool box 13, Figs. 2 and 4, and provide this pneumatic 12 with an arm 14 which is connected with a link 15 which extends to and is pivotally connected with a crank arm 16 on the rock shaft 9. Thus the expansion and collapse of the pneumatic 12 will actuate the crank arm 16 and thereby rock the shaft 9 so as to throw the arms 7 and 8 into and out of engagement with the roll 1.

I also desirably provide means by which the roll 1 may be retained in the longitudinal adjustment to which it is set by means of the arms 7 and 8. The form of arrangement shown comprises a lever 18 pivoted at 19 to the left hand end (Fig. 1) of the music box 13, as shown in Fig. 3. This lever 18 is arranged to swing to and contact with a rod 20 which is connected by a clip 21 with the spindle 22, for the left hand end, (Fig. 1) of roll spindle 22, the other end of the

rod 20 being bent upwardly as at 28 to engage the right hand roll spindle 24, whereby the rod 20 and music roll spindles 22 and 24 move in unison lengthwise of the roll 1. 5 Thus a swinging movement of the lever 18 to the position shown in dotted lines in Fig. 3 will cause the lower end of said lever to engage and act against an end portion of the rod 20, and thereby engage and lock said 10 rod so as to prevent longitudinal movement of the same and thereby prevent also longitudinal movement of the roll 1. As an arrangement for operating the lever 18 I show a second pneumatic 25 secured to the back 15 of the box 13 and having its swinging member provided with a finger or clip 26 (Fig. 2) adapted to act upon the upper end of the lever 18, so that when said pneumatic 25 is collapsed the lever 18 will be swung so as 20 to cause its lower end to engage and bind the rod 20. A tube or pipe 27 is shown connected with the pneumatic 25 and another tube 28 running from the pneumatic 25 to the pneumatic 12. The tube 27 is 25 understood to be connected with the wind chest or other duct or passage connecting with the wind inducing apparatus so that when pumping is begun and playing pressure produced both of the pneumatics 25 30 and 12 will be exhausted and collapsed, thereby automatically locking the roll 1 and swinging the arms 7 and 8 upwardly and disengaging them from said roll 1. Thus after the roll 1 has been put in position and 35 its end connected with the take-up spool 3, and before playing starts, said roll 1 may be adjusted until the arms 7 and 8 fit between the flanges of the roll, thus properly positioning said roll for proper trackage. Then 40 pumping may be begun, thereby actuating the pneumatics 12 and 25 and thus the arms 7 and 8 will be automatically disengaged from the roll 1, and said roll locked against longitudinal movement and thus maintained 45 in position for proper trackage throughout the playing. When this roll has been played the pneumatics 12 and 25 will expand, thereby releasing the rod 20 and also allowing the arms 7 and 8 drop. Inasmuch however, as the arms 7 and 8 may be easily adjusted by hand, they may be raised by hand 50 so as to release and remove the music roll 1. Another roll may then be put in position and like the first one it may be adjusted 55 by means of the arms 7 and 8 to a position which has been predetermined as the correct one for the trackage of the music sheet. This roll when playing starts will be automatically locked in position and the arms 7 60 and 8 removed so as to avoid interference with the playing. This roll also may be removed after playing and another roll inserted and adjusted in proper position and

then played. Thus it will be seen that each roll may be adjusted in proper tracking position, but this is done without any reference to the tracker board and without any experimentation to aid the perforations in the music sheet into register with the apertures in the tracker board. The proper position for the 70 music sheet is instantly determined when the roll is placed in position and the arms 7 and 8 allowed to drop and thus quickness and facility in adjustment and playing are secured, and the result is obtained without any 75 experimentation or adjustment of the sheet relatively to the tracker board.

Referring to the modification shown in Figs. 6, 7 and 8, rods or arms 7^a and 8^a are shown mounted on the rock shaft 9 and 80 these rods 7^a and 8^a are provided at their outer ends with clips or roll engaging devices 30. These latter are pivotally mounted upon the ends of the arms or rods 7^a and 8^a, so that they can tilt or swing, as 85 shown in dotted lines in Fig. 6. Each member 30 is provided with a pointed end 31 and has its opposite end cut away as at 32. Thus the pointed end is heaviest and tends to swing down and remain in a lower position with the device inclined as shown in Fig. 6. A handle 33 is also mounted upon the rock shaft 9. Thus the shaft 9 may be rocked so as to cause the members 30 to move toward and away from the roll 1, as 90 shown in dotted and full lines in Fig. 7. With the members 30 inclined so that their pointed outer ends are downwardly as shown in dotted lines in Fig. 6, the shaft 9 is rocked downwardly by the handle 33 so that 95 one or both of the members 30 engage the flange or flanges at the ends of the roll 1. If but one member 30 engages a flange, a further downward movement of the handle 33 will cause a further downward movement of the 100 arms 7^a and 8^a, and thus will cause a shifting longitudinal movement of the roll 1 by the action upon it of the member 30 engaging one of the roll flanges. This shifting longitudinal movement will continue until the 110 roll is moved so as to cause the other member 30 to engage the other roll flange, the roll, as it were, being moved up to said other member 30. Thus the roll will be properly and accurately positioned or centered by the two members 30 engaging its flanges, the roll being in this way properly and accurately adjusted for the proper trackage of the music sheet. The members 30 will in the meantime have acquired a 115 more nearly horizontal position; if the roll is the usual length they will have acquired practically a horizontal position as shown in solid lines in Fig. 6. In this modification the shaft 9 is preferably automatically 120 swung upwardly and the roll locked in position 125

position by the means described in connection with the first described structure, but as said automatic swinging and locking means are described in connection with said other construction they will not be described here,

It will be seen that the pivoted or tilting members 30 permit the successful operation of the device with rolls of somewhat different length and that such rolls will be properly and accurately adjusted, notwithstanding their difference in length.

It will be understood that changes and modifications may be made without departing from the spirit of the invention.

What I claim is:

1. The combination with means for supporting a music roll, of means for engaging said roll for adjustment, said means comprising a pivoted finger and a supporting structure for said finger by which the finger can be moved so as to engage and move the roll.

2. The combination with means for supporting a music roll, of means for engaging said roll for longitudinal adjustment, said means comprising a pair of pivoted fingers and a supporting structure by which said fingers may be moved toward and away from the roll so as to engage the same and cause an adjustment of the roll.

3. The combination with means for supporting a music roll, of means for engaging the roll for adjustment, said means comprising a pair of pivoted fingers weighted so that one end will swing downwardly, and a movable supporting structure on which said fingers are mounted, said structure holding said fingers in position between the flanges at the ends of the roll and the fingers being arranged so that their weighted ends are toward the flanges, whereby said fingers may engage the flanges and automatically adjust the roll.

4. Means for adjusting a music roll comprising a pair of fingers having pointed weighted ends, and a movable supporting structure on which said fingers are pivotally mounted, said supporting structure being arranged to hold and move the fingers toward and away from the roll between the flanges thereof, whereby the weighted ends of the fingers may strike first against the music sheet on the roll and then slide along said sheet and act against said flanges so as to adjust the roll in one direction or the other.

5. The combination with a music roll and means for supporting the same, of a rock shaft extended lengthwise of the music roll, means carried by said rock shaft and extended laterally from the same, said means being adapted to engage the flanges of the music roll, and means for automatically rocking

said rock shaft so as to move it toward the music roll.

6. Means for engaging and adjusting a music roll comprising a longitudinally adjustable rock shaft provided with transversely extending arms, and fingers having weighted ends pivotally mounted at the ends of said arms, said transverse arms being located between the music roll flanges and said fingers being arranged with their weighted ends extending toward the flanges so as to engage the same and shift the roll when said rock shaft is rocked.

7. The combination with means for supporting a music roll, of means for engaging the roll to adjust it in position, means for locking the roll in adjusted position, and means for disengaging the engaging means and actuating the locking means.

8. The combination of means for supporting a music roll, a swinging arm for engaging said roll, and a pneumatic for actuating said swinging arm transversely to the axis of the music roll.

9. The combination of means for supporting a music roll, swinging arms for engaging the ends of said roll, a rock shaft on which said arms are mounted, a pneumatic, and a crank and link connection between said pneumatic and said rock shaft for actuating the latter by the operation of the pneumatic.

10. The combination of means for supporting a music roll, a rod extending longitudinally of said music roll and connected with said roll supporting means, a lever for engaging said rod, and a pneumatic for actuating said lever.

11. The combination of means for supporting a music roll, a rock shaft provided with one or more arms for engaging one or both of the flanges at the ends of the music roll, a pneumatic combined with means whereby said pneumatic operates said rock shaft so as to disengage said arm from the music roll, a rod extending longitudinally of the music roll, a lever for engaging said rod to lock the same, and a second pneumatic for actuating said lever.

12. The combination with a music roll and means for supporting the same, of a rock shaft extending lengthwise of the music roll and provided with laterally extending arms having their free ends provided with means for engaging the flanges of the music roll, and means for automatically swinging said rock shaft so as to move it toward the music roll to cause engagement of said roll flanges.

13. The combination with a music roll and means for supporting the same, of a rock shaft extending lengthwise of the music roll and provided with laterally extending arms

having their free ends provided with means for engaging the flanges of the music roll, means for automatically swinging said rock shaft so as to move it toward the music roll 5 to cause engagement of said roll flanges, and means for automatically rocking said rock shaft in a reverse direction to retract said music roll engaging means from said roll.

Copies of this patent may be obtained for five cents each, by addressing the "Commissioner of Patents, Washington, D. C."

In witness whereof I hereunto subscribe my name this 29th day of October, A. D., 1915.

ADOLPH PETER GUSTAFSON.
